INVENTOR

UNITED STATES PATENT OFFICE

95,147

DESIGN FOR A SHOE

Christy Reggie, South Braintree, Mass.

Application February 12, 1935, Serial No. 55,371

Term of patent 3½ years

To all whom it may concern:

Be it known that I, Christy Reggie, a citizen of the United States of America, residing in South Braintree, county of Norfolk, and State of Massachusetts, have invented a new, original, and ornamental Design for a Shoe, of which the following is a specification, reference being had to the accompanying drawing, forming part thereof, wherein,

I claim:

The ornamental design for a shoe, substantially as shown.

CHRISTY REGGIE.
